REVERSIBLE CLOSE QUARTER DRILL

Leon F. Meunier, Cleveland, Ohio, assignor to Chicago Pneumatic Tool Company, New York, N. Y., a corporation of New Jersey

Application August 3, 1943, Serial No. 497,167

9 Claims. (Cl. 74—472)

This invention relates to portable power driven close quarter drills or tools adapted for tapping, drilling, screw driving, reaming etc., and particularly to reversing means for the mechanical drive thereof.

The general object of the invention is to provide a portable drill or tool of the type indicated with special reversing means capable of driving the drill in either direction at will, although the prime mover furnishing the power is capable of rotation only in one direction. The use of a unidirectional motor overcomes certain well known disadvantages of prior drills in which motors of the reversible type are resorted to. In the case of a pneumatic motor, the reversing throttle structure and complicated porting arrangement add to the bulk, weight and cost of the drill. In an electric tool, on the other hand, the sudden reversal of power supply while the motor is running under its momentum would cause dangerous current surges, and therefore it is usually found necessary to provide a special brake to stop the motor mechanically before the switch can be thrown into reverse.

A specific object is to enable the operator to control both the reversing gears and the power connections to the motor by the manipulation of a single control element, which also forms a handle for supporting the drill.

Another object is to provide a portable power driven tool or drill with a practical type of reversing means which is reliable and durable despite the limited space available in such a tool, thereby eliminating any need for bulky or heavy conventional reversing devices.

A further object is the provision of a high ratio speed reduction mechanism to enable the drill spindle to be driven by a high speed, high frequency electric motor, with consequent freedom from vibration during operation.

It is also an object to embody the principles of the invention in such a efficient design of the parts of a portable power driven tool that lightness of the resulting assembly and accessibility of the interior for repairs as well as replacement of parts without sacrificing efficiency, power or smoothness of operation will characterize the tool as a whole.

Other objects and the various advantages inherent in the nature and construction of the invention and accruing from the application thereof in actual practice will appear more fully in detail as this specification proceeds.

In order to facilitate ready comprehension of the novel features and constructional details, the

invention is illustrated in the accompanying drawings forming part hereof and in which:

Fig. 1 is a side elevation of a portable power driven close quarter drill or tool made according to this invention and embodying the salient features thereof, the view indicating how the tool may be held in the hands of an operator;

Fig. 2 is a vertical longitudinal section of the same tool serving to disclose interior details of construction and relations of parts;

Fig. 3 is a cross section of the apparatus taken on line 3—3 in Fig. 2;

Fig. 4 is another cross section of the same taken approximately on line 4—4 in said Fig. 2;

Fig. 5 is also a cross section of said apparatus taken on line 5—5 in Fig. 2, looking rearward;

Fig. 6 is a fragmentary view, looking forward, showing parts of the apparatus disclosed in Fig. 5 occupying an intermediate or neutral position;

Fig. 7 is a further cross section of the apparatus taken on line 7—7 in Fig. 2 showing substantially the same parts from the side opposite that shown in Fig. 5;

Fig. 8 diagrammatically illustrates a different stage of operation of the movable parts shown in Figs. 5 and 7, the view being taken along line 8—8 in Fig. 2;

Fig. 9 also illustrates diagrammatically the same parts at an opposite stage of operation;

Fig. 10 is a plan view of the apparatus of Figs. 1 and 2 with the top removed to reveal interior detail, an intermediate portion of the length being broken away;

Fig. 11 is an enlarged perspective view showing a pair of gear segment levers of Figs. 5 to 9;

Fig. 12 is a fragmentary horizontal section of the apparatus of Fig. 2 as taken on line 12—12; and

Fig. 13 is another fragmentary horizontal section of the same taken on line 13—13 in the same Fig. 2.

Figs. 10, 12 and 13 are drawn to a smaller scale than Figs. 3 to 9 inclusive but to a larger scale than Figs. 1 and 2.

The same references indicate the same or like parts throughout the views.

In power driven tools of the portable type and especially in close quarter drills utilizing ratchet lever and pawl means for rotating the tool spindle, it is very desirable to enable reversal of rotation of the tool spindle at will. Ordinarily this would entail use of a reversible motor or, if a non-reversible motor were used, conventional reversing mechanism would be included which is more or less bulky and heavy and not well suited for

use in a portable tool, not to mention that a reversing switch for an electric motor together with a brake for the latter would include an element of danger due to the heavy current required to drive such a motor and particularly the high amperage surge which would be built up when stopping the motor and reversing the same.

It is therefore proposed to avoid reversing the motor and instead introduce a very effective and simple reversing device which is combined with a ratchet drive, together with complete remote control of the apparatus involved which substantially fulfills the foregoing objects while avoiding the mentioned disadvantages and in addition forming a practical solution to several problems in this field.

Hence referring again to the drawings, in the practice of the invention an electric motor generally indicated at 14 is enclosed within a casing 15 (Fig. 2) and comprises a rotor 16 mounted on a shaft 17 which is rotatable in bearings 18 and 19. The shaft 17 carries upon its forward end a pinion 20 axially retained on the shaft by a collar 21 and meshing with a gear 22 fixed on a transverse shaft 23. In order to ventilate and cool the motor during operation, a conventional fan 24 is fixed on the motor shaft 17 within a plurality of peripheral openings 25 at one end of the motor casing 15 and tends to draw out air passing through the motor from a plurality of rear side openings 26 in said casing. Rearwardly the motor bearing 18 has an outer race 27 retained in position by means of a plate 28 held by a screw 29 on the rear wall 30 for the motor casing, while the front bearing 19 has the outer race 31 thereof retained in place in the forward end wall or partition 32 by means of a plate 33 held on said wall by a screw or screws 34. The front end wall or partition 32 is secured by bolts 32a (Fig. 4) to the end of motor casing 15 and to said partition is attached a ratchet drive casing 35 by any suitable means known in the art and provided with bearings 36, 36 for the transverse shaft 23 which may be termed the drive shaft.

Upon this drive shaft a spur gear 37 is rigidly secured which meshes with a larger gear 38 fixed on a crank-shaft 39 rotated in bearings 40, 40 mounted in casing 35 in parallelism with bearings 36, 36.

The crank-shaft 39 is formed with two correspondingly opposite cranks 41, 42 individually oscillating a pair of similar ratchet members 43 by means of bearing blocks 44 slidably mounted between gibs 12 and 13 (Figs. 2, 10 and 12) forming the rear ends of said members, while the other or forward ends of the latter are each formed with an internal ratchet 45. Each ratchet surrounds a rotary tool spindle 46 mounted in an upper bearing 47 and a lower bearing 48 located in the forward end or head 49 of casing 35, the lower bearings being removably held in position by a screwed ring 50 which also allows removal of the tool spindle for replacement or repairs. The latter spindle is of more or less conventional construction, and is recessed to receive the lower end of a feed screw 51 supported in a collar 52 fitting into the upper hub portion 53 of casing head 49.

The ratchet members are oscillated at their rear ends by the cranks 41, 42 to which they are connected and in order to translate their oscillations into torque impulses imparted to the drill spindle, the latter is provided with two groups of centrifugal pawls 55, 55 and 56, 56 recessed into pockets 57 and 58 in the sides of the spindle so

that said pawls may be withdrawn within the section outline of said spindle as particularly evident in Figs. 10 and 12.

Further each pawl 55 and 56 is retained in assembled association with the spindle, primarily by the same having an enlarged cylindrical rear end 59 occupying a corresponding seat 60 in the body of the spindle which allows the pawl to swing from withdrawn position in pockets or recesses 57 or 58 within the spindle outline out into active contact with the teeth of internal ratchet 45. Each pawl is also confined in position by the walls of the pocket in which it is located, and in each case a spring 61 is preferably recessed in the rear wall of the pocket involved and also in the corresponding pawl so as to tend to swing said pawl out into active engagement with the ratchet surrounding the spindle. If then one set of pawls consisting of pawls 56, 56 as shown in Figs. 10 and 12 are free to swing out and engage internal ratchet 45 as urged by springs 61, assuming that the motor is actively driving crankshaft 39, the latter will rapidly oscillate ratchet members 43 and by means of said pawls 56 engaging the ratchets within said members will consequently rotate spindle 46 in clockwise direction.

Should the mentioned set of pawls be withdrawn into their pockets by suitable means and the other set consisting of pawls 55, 55 be released instead, the oscillation of the ratchet members, although still continuing in the same manner as indicated, will nonetheless cause the spindle to be rotated by said pawls 55 in the opposite or counterclockwise direction. While merely two opposed sets of pawls may be arranged to form a group to be operated by both ratchet members, it is preferred to use two such groups of pawls in superimposed relation, one group for each ratchet member, with the lower group extending to the bottom of each pocket 57 or 58 in the spindle while the upper group rests directly on the lower group and extends up to the inner race 63 of bearings 47 (Fig. 2), thereby preventing axial displacement of the pawls in both groups.

Thus far it has been disclosed how the motor, by causing continuous rotation of the crank-shaft and therefore also continual oscillation of the ratchet members, thereby causes rotation of the tool spindle 46. It is consequently now in order to consider the means for controlling the direction of rotation of the spindle caused by the oscillation of the ratchet members while the motor rotates exclusively in one direction. To this end, spindle 46 carries a gear 64 keyed thereto at 65 so as to be positively rotated therewith, said gear meshing with a pinion 66 splined by a key 67 in a keyway 62 on a vertical reversing shaft 68 which is parallel with the spindle and rotatable thereby in a lower bearing 69 and an upper bushing 70 fixed in casing 35 in a position intermediate the spindle and crank-shaft 39. Reversing shaft 68 is axially slidable and formed with a reduced portion 71 surmounted by a wide head 72 at the upper end thereof. Referring to Figs. 2, 3 and 13, a rack 73 which is bifurcated rearwardly by a slot 74 straddles the reduced portion 71 and is positively displaced in axial directions with said shaft due to its association with the reduced portion between head 72 and shoulder 75 defining the upper and lower limits of said reduced portion. While the rack is thus assembled with the reversing shaft, the latter is rotatable with the reduced portion thereof in slot 74 of the rack and in order to positively hold said rack against rotation with the shaft, the rack in all positions of

axial displacement is located between the sides of an open vertical slot 76 in the upper end of bushing 70.

As may best be seen in Figs. 3 and 13, a sector lever 77 meshes with the rack and is fixed on the forward end 78 of a transmission shaft 79 (to be further described hereinafter) said end 78 being square and fitting a corresponding square hole in said lever to ensure positive rotary movement of the latter with said shaft. This rotary movement is limited to partial rotation with corresponding limited rise or fall of the rack as well as vertical shaft 68 for the purpose of determining the direction of rotation of the spindle.

Upon shaft 68 is a reversing pinion 80 meshing with a pawl selecting or reversing cam gear 81 rotatably mounted on the spindle 46 and provided with an integral sleeve 82 which virtually forms an integral hub slidably mounted on aforesaid reversing shaft, while a transverse reversing pin 83 projects rigidly from the side of said shaft and extends slidably into an oblique slot 84 in said sleeve. The mentioned cam gear 81 is located on an intermediate level in which the same may engage about both the upper and lower groups of pawls and has upon its inner periphery a group of opposite cam recesses 87, 87 and 88, 88 so relatively spaced apart with respect to the location of the pawls, as to be capable of alternatively releasing pawls 55 or 56 into engagement with the ratchets 45 and cause the oscillation of the ratchet members to effect rotation of the spindle in clockwise or counterclockwise direction accordingly.

In order to ensure retention of pin 83 in useful association with reversing shaft 68 an outer sleeve 85 is mounted upon sleeve or hub 82 exteriorly of said pin and extends between pinions 66 and 80.

As already intimated the two ratchet members 43 oscillate uniformly in the same manner irrespective of the resulting direction of rotation of the spindle or of which set of pawls is active, and both members have a large clearance opening 86 to allow said members full freedom to oscillate without contact with sleeves 82 or 85 or with bushing 70.

It is evident that if transmission shaft 79 is turned counterclockwise (looking forward) so that sector lever 77 in meshing with rack 73 will raise reversing shaft 68 with its pin 83, the latter pin will rise through slot 84, and due to the oblique form of the same, the sleeve 82 and pinion 80 will be partially rotated toward the left from the position shown in Fig. 3, or angularly displaced in clockwise direction (looking downward) with respect to reversing shaft 68 and the lower pinion 66.

The mentioned pinion 66 is prevented from rotating upon said reversing shaft as it is slidably splined to the same. As pinion 66 meshes with gear 64 and the latter is fixed on the spindle, and as pinion 80 meshes with reversing cam gear 81 surrounding the spindle, the effect of the angular displacement or partial rotation of pinion 80 will be that cam gear 81 meshing therewith will also be partially rotated or angularly displaced on the spindle 46 in counterclockwise direction into a position wherein pawl clearance or cam recesses 87 in the cam gear will register with the outer extremities of pawls 55 and allow the same to swing out into active engagement with ratchet 45, causing the ratchet members to rotate the spindle in counterclockwise direction. If the transmission shaft 79 with its sector lever 77 is partly rotated in clockwise direction the

same will cause the rack and the reversing shaft to lower into the position shown in Figs. 2 and 3, the slotted sleeve and reversing pinion will then be angularly displaced by pin 83 in counterclockwise direction with respect to said reversing shaft 68 and pinion 80. This will cause corresponding rotation or angular displacement of cam gear 81 in clockwise direction so as to assume the position indicated in Fig. 10 wherein cam recess 88 will register with the ends of pawls 56 so as to release the same and allow them to swing freely out into operative contact with ratchets 45 and allow oscillation of the ratchet members to cause clockwise rotation of the spindle. The cam recesses 87 are properly spaced from the cam recesses 88 to ensure that when one set of pawls is released for contact with the ratchets the other set is swung back by the form of the interior cam recesses of the cam gear into the pawl pockets within the outline of the spindle and are therefore idle.

The ultimate control of the motor and the setting of the direction of rotation of the spindle will now be considered and may actually be termed a remote control of the operation as a whole.

A control casing 89 is secured to the rear 30 of the motor casing 15 and within the same is fixed a supporting plate 90 by means of screws 91 or the like and carrying an electric service switch 92 provided with a snap switch arm 93 projecting rearwardly through said plate 90. The motor is connected to the switch and both the motor and switch also connected to a current cable 94 in well known manner (not shown in order to avoid obscuring the view) the cable issuing from a rear hub 95 on casing 89 to the outside for connection with the electric mains. In the raised position of the switch arm shown in Fig. 2 the current is assumed to be off and the motor idle, and hence any means serving to draw said switch arm down into a low position will thereby turn on the current and start the motor. As this motor is non-reversible no facilities for reversing the same are necessary nor are in fact any further facilities for electrically or mechanically controlling the motor required. On the other hand, a single manual control about to be described is used for simultaneously controlling operation of the motor and determining the direction of rotation of the drill or tool during operation.

Upon the end 96 of control casing 89 (Figs. 1, 2 and 10) a hub 97 projects rearwardly and within the latter is rigidly secured the end of a sleeve 98 serving as a support for a manually rotatable operating sleeve 99, a screw 100 being screwed into the outer extremity of supporting sleeve 98 and provided with a flange 101 serving to retain sleeve 99 axially against displacement on said supporting sleeve. Within the latter sleeve is mounted a rotatable control sleeve 102 extending from the end screw 100 beyond the casing end wall 96 and terminating within said end wall in a one tooth gear sector or cam disc 103 and rigidly connected for simultaneous rotation with the outer manually rotated sleeve 99 by means of a stud or screw 104 which extends inwardly from said manual sleeve 99 into control sleeve 102 through a transverse clearance slot 105 in the supporting sleeve 98.

The cam disc 103 carries upon its periphery a single gear tooth 106 adapted to mesh with a corresponding single tooth space 107 in an intermittent gear sector or lever 108 secured on the

rear end of transmission shaft 79 already mentioned. At the sides of the tooth space 107 the gear sector is formed with two similar profile portions 109, 110, either one of which will remain at rest adjacent to the outer circular peripheral portion 111 of disc 103 and will prevent further rotation of the gear sector by said cam disc after the single tooth 106 has engaged in the tooth space 107 and shifted said disc by rotation from an intermediate neutral position indicated in Fig. 6 to either side as indicated in Figs. 8 and 9.

The manual control of transmission shaft just described forms a remote control of the previously described reversible ratchet drive mechanism for the tool spindle, but simultaneously controls operation of the switch 92 as well. Thus a pair of fixed bolts or posts 112, 113 project rearwardly from the switch supporting plate 90 within control casing 89 and serve as pivot mountings for a pair of gear sector levers 114, 115 pivoted at their outer ends on said posts, and being provided at their inner adjacent ends with mutually meshing gear teeth 116, 117 respectively, so that both levers positively follow each other in their pivotal movements about their pivot posts 112, 113. A switch lever 118 is also mounted upon post 113 and secured in rigid association with gear sector lever 115 by means of a pin 119 which not only extends into said levers 115 and 118 but in addition also projects rearwardly from sector lever 115 into a clearance recess 120 cut into the junction of the gear sector or cam disc 103 with the control sleeve 102.

The mentioned pin 119 also serves another purpose than carrying along lever 118 with sector lever 115 as will also appear. A corresponding pin 121 projects rearwardly in similar fashion from the sector lever 114 into mentioned clearance recess 120, while between the two pins 119 and 121 is an inwardly projecting cam 122 integral with control sleeve 102 and cam disc 103 and occupying part of said recess. Then to complete the switch operating mechanism, the switch lever has an open slot or recess 123 at the inner free end thereof for receiving the snap switch arm 93 of switch 92.

It will now be evident that when the tool as a whole is held in operative position by the left hand indicated at 124 in Fig. 1 and the right hand 125 seizes the manual operating sleeve 99, a quarter turn of said sleeve to the left will cause inner control sleeve 102 and sector or disc 103, starting from the neutral position of Fig. 6, to shift first to the position shown in Figs. 5 and 7 in which the tooth 106 has just left the corresponding tooth space 107 in lever 108 and set the latter in position with its profile portion 110 in contact with the circular peripheral portion 111 of the cam disc 103, which effects a partial clockwise rotation of transmission shaft 79. At the forward end of the shaft the gear sector 77 meshing with rack 73 is correspondingly rotated with shaft 79 and will lower the rack with its shaft 68 into the position of Fig. 3, causing the pin 83 by descending to the bottom of oblique slot 84 to rotate sleeve or hub 82 and reversing pinion 80 counterclockwise. The pawl selector or cam gear 81 will thereby be rotated in clockwise direction to assume the position shown in Fig. 10 with pawls 56 actively engaging the internal ratchets 45 of ratchet members 43 preparatory to driving tool spindle 46 in clockwise direction.

Proceeding with the manual rotation of operating sleeve 99 and its sector or disc 103 from the position appearing in Figs. 5 and 7 to that

indicated in broken lines in Fig. 8, it will be noted that while sector lever 108 and shaft 79 remain in their attained positions, the interior cam 122 within control sleeve 102 engages against pin 119 (see Fig. 6) on gear sector lever 115 and thereby brings the same downward and with it the switch lever 118. This operation carries the switch arm 93 down and thereby operates the switch to close the circuit of the motor which immediately results in operation of the tool with the spindle and the tool carried thereby rotating in clockwise direction until manual sleeve 99 is returned clockwise to starting position, when the inner control sleeve 102, disc 103 and sector 108 will resume their original neutral positions indicated in Fig. 6. The switch arm 93 is assumed to be self-restoring so that if released said arm will return automatically upward and thereby break the circuit by opening the switch. Such movement of the switch arm may be caused by spring means built into the switch (not shown), but the mentioned upward movement will thus carry lever 118 and sector lever 115 upward with the switch arm, and as sector lever 114 meshes with sector lever 115, the latter will likewise be restored to upper initial position shown in Figs. 5 and 7, with pins 119 and 121 disposed in their upper positions and interior cam 122 in neutral intermediate position as indicated in said Fig. 6.

When it is desired to operate the tool with a drill, tap or die rotating in counterclockwise direction, turning the operating sleeve 99 and thereby the inner control sleeve 102 and disc 103 to the position indicated in Fig. 9 will cause rotation of sector 108 and transmission shaft 79 in counterclockwise direction, raising the rack 73 and shaft 68 with its pin 83 at the front end of the apparatus. This rotates sleeve 82 clockwise so that simultaneous rotation of its pinion 80 will correspondingly rotate cam gear 84 counterclockwise to release pawls 55 into cam recesses 87 in said gear for contact with ratchets 45. The spindle 46 is then conditioned for counterclockwise rotation upon subsequent oscillation of the ratchet members 43 by rotation of crank-shaft 39 through the drive shaft 23 by the motor. Continued turning of the manual operating sleeve 99 to the right brings interior cam 122 into contact with pin 121 on sector lever 114 and lowers the latter into the position of Fig. 9 which corresponds to the position said sector lever occupied in Fig. 8. In this case sector lever 114 has brought down sector lever 115 with the same and thereby also switch lever 118, with the result that switch arm 93 has also been operated downward to close the switch as before, the motor being thereby started to rotate the drill or other tool in the intended counterclockwise direction. It is therefore of no consequence in which direction the operating sleeve is rotated for starting the motor, as in any case the motor will be positively started to operate in its one direction while the specific direction in which the manual sleeve is turned will instead determine the direction in which the operating tool will be driven by the motor through the alterable interior drive mechanism within the tool casing.

It is of course desirable to have the operating sleeve self-restoring to intermediate neutral position when released by the hand, so that the choice of the direction of rotation of the tool is as readily made with respect to one direction as in the opposite direction, while also including the release and opening of the electric switch. For this pur-

pose the end screw 100 has a hollow projection 126 into which the rear end of a plunger 127 slidably extends, the other end of the latter terminating in a head 128 engaging against a transverse pin 129 projecting at both ends through a pair of longitudinally disposed operating slots 130 in supporting sleeve 98. This pin is resiliently urged forward toward the forward extremities of slots 130 by means of a spring 131 mounted on the plunger between head 128 and screw 100, and also extends through opposite pairs of V-slots 132, 133 in the manual operating sleeve 99 and inner control sleeve 102 (Figs. 2 and 10). The apex of the angle in each V-slot is directed forward so that said pin will bear against the inclined edges of the slots and tend to cam in the outer and inner slots into a neutral central position under pressure of spring 131 when the operating sleeve is released by the operator. The outer sleeve 99 is recessed by a reduced portion 134 in order to accommodate a ferrule or covering ring 135 serving to conceal the mentioned slots and retain pin 129 in place and thereby finish the appearance of the operating sleeve.

While the motor casing 15, reversing drive casing 35 and control casing 89 have been specifically described as adjacent casings connected into a series, such construction is merely a convenience and hence for the purpose of this invention these casings may be considered generically to be a single casing, that is, the casing of a power operated tool as a whole.

It is self-evident that the various operating parts of the apparatus may be made of any suitable metals or alloys and that the casing, for example may be made of a light metal or alloy or even of any suitable plastics in order to lighten the tool as a whole. On the other hand the pawls may be increased or decreased in number and located in the ratchet members and contact with ratchet teeth on the tool spindle if so desired, and if a common snap switch is used without a self-restoring arm the gear sector levers may instead be restored by spring means raising the same to neutral or idle position upon return of the operating sleeves to neutral idle position. Other modifications within the purview of the invention may be resorted to as found best in practice and according to the scope of the appended claims.

What is claimed is:

1. In a portable power driven tool having a casing with a rotatable tool spindle journaled therein and a uni-directional motor having switch means and providing the power for driving the tool spindle, the combination of reversible driving means for transmitting the drive of the motor to said tool spindle in either direction, including at least one ratchet member oscillating adjacent to the tool spindle when operated by the motor, at least two oppositely disposed pawls associated with the tool spindle for individual operative engagement with said ratchet member for rotating the tool spindle in one direction by means of one pawl and alternatively in the opposite direction by means of the other pawl during operation of said ratchet member, a movable reversing member closely associated with said tool spindle for retracting one pawl into a recess within the outline of the latter spindle and simultaneously releasing the opposite pawl for engagement with the ratchet member and vice versa, and a manipulative member for operating said switch means after moving said reversing member to select the direction of rotary movement to be imparted to said tool spindle.

2. In a portable power driven tool having a cas-

ing with a rotatable tool spindle journaled therein, a non-reversible driving motor in said casing, and operative means driven by said motor, the combination of reversible driving means actuated by the motor including at least one ratchet member having a ratchet surrounding the tool spindle, at least two oppositely directed pawls pivoted in recesses in said tool spindle and individually capable of being swung from said recesses into active engagement with the teeth of said ratchet and by oscillation of said ratchet member rotating the spindle in clockwise or counterclockwise direction according to the pawl engaging with said ratchet, said operative means oscillating one portion of said ratchet member and thereby partly rotating the latter about said spindle, means resiliently urging said pawls toward said ratchet for engagement therewith, a cam associated with the spindle and capable of adjustment from one position in which said cam holds one pawl inactive in its recess while allowing the other pawl to engage freely against the ratchet, and to another position in which the cam allows the one pawl to engage freely against said ratchet while holding said other pawl inactive in its recess, and manually operated means movable in opposite directions from an intermediate neutral position for adjusting said cam to either position of adjustment at will, the manually operated means tending to return to neutral position when released.

3. In a portable power driven tool having a casing with a rotatably mounted tool spindle located at one end of the casing, drive means for causing rotation of the spindle, and a rotatable cam having means associated therewith for controlling the direction of the rotary movement imparted to said tool spindle by said drive means, the combination of manually operated means for rotating the cam including a manually controlled member accessible upon the other or far end of said casing remote from said one end of the latter, a transmission shaft extending a distance through said casing, means associated with the forward end of the shaft for communicating rotation thereof to the cam for selecting the direction of rotation intended for the tool spindle, and means associated with the other end of said shaft for communicating movement of the manually controlled member to said shaft to partly rotate the latter and thereby control the direction of rotation imparted by the drive means to the tool spindle.

4. In a portable power driven tool having a casing with a rotatably mounted tool spindle, drive means for causing rotation of the latter, and a rotatable cam having means associated therewith for controlling the direction of the rotary movement imparted to said tool spindle by said drive means, the combination of a gear embodying said cam surrounding the tool spindle and mounted to be independently rotatable about the same, a pinion meshing with said gear and having a hub forming a sleeve, a reversing shaft slidably supporting said pinion and its sleeve, a pin on said reversing shaft projecting into a cam slot in said sleeve, a second pinion slidably splined on said shaft for longitudinal movement of the shaft with respect to said pinions, a second gear mounted on the tool spindle for positive rotation therewith, and a lever engaging a portion upon said shaft and capable of axially sliding the latter with respect to said pinions and thereby causing angular displacement of the first mentioned gear with respect to the tool spindle and the second gear upon said tool spindle, and

a manually operated member connected to said lever for operating the latter at will.

5. A portable power driven tool comprising an elongated casing having a rotatable tool spindle journaled in one end thereof, a non-reversible driving motor in said casing, reversible driving means driven by the motor and operatively associated with the tool spindle and capable of transmitting driving movement from said motor to said tool spindle for rotating the latter in clockwise or counterclockwise direction, said reversible driving means having an adjustable member controlling the direction of rotary movement imparted to the tool spindle by said driving means, a manually operated control member accessible upon the other or far end of the casing and adjustable to either one of two extreme positions to determine said direction of rotation of the tool spindle, a gear sector rotatably adjustable with said control member, a sector lever engaged by said gear sector and shiftable thereby into either one of two extreme opposite positions, a transmission member connected to said sector lever extending toward the first mentioned end of the casing, and adjustable means associated with said transmission member within said end of the casing for communicating changes of adjustment of said sector lever and transmission member to the adjustable member of said reversible driving means for ultimately determining the direction of rotation of the tool spindle by adjustment of said manual control member.

6. A portable power driven tool including a casing, a tool spindle rotatably mounted in one portion of said casing, a non-reversible motor associated with said casing, reversible driving means in said casing driven by said motor, an adjustable member operatively associated with said driving means and capable of adjustment to two extreme opposite positions for controlling corresponding clockwise or counterclockwise rotation of said tool spindle by said driving means according to the attained position of said adjustable member, a manual control member accessible upon another portion of the casing and shiftable to either one of two positions for initially determining the direction of rotation of said tool spindle, motor control means within said casing serving to control operation of said motor, transmission means extending from the vicinity of said manual control member toward said driving means, adjusting means operable by said transmission means for adjusting the adjustable member to one of its two effective positions, means operatively associated with said

5 manual control member for operating said transmission means and thereby ultimately controlling the direction of rotation of said spindle by means of said manual control member and for 10 allowing further shifting of the latter control member beyond either of its two effective positions for operating the transmission means, and further means associated with said manual control member effective to operate said motor control means upon adjustment of said manual control member beyond either of said two effective positions thereof after having initially determined the direction of rotation to be imparted to the tool spindle by the driving means.

15 7. A portable power driven tool according to claim 6, wherein the non-reversible motor is an electric motor and the motor control means includes electrical means of the class consisting of electric circuit breakers and switches.

20 8. A portable power driven tool according to claim 6, wherein the casing is elongated with the tool spindle rotatably mounted in one end thereof and the manual control member is located at the other end of the casing, and wherein the 25 transmission means includes a partly rotatable shaft extending lengthwise through the major portion of the length of said casing from the vicinity of the manual control member to the vicinity of the driving means, said partly rotatable shaft being controlled at the one end by said manual control member and at the other end communicating its movement to said driving means.

9. A portable drill comprising a casing; a unidirectional electric motor supported thereby; a switch for said motor; a tool spindle supported for movement in opposite directions relative to the casing; a transmission between said motor and spindle including reduction gearing and selectively operated reversing means for controlling the direction of rotation of the spindle; a handle for supporting said casing and having a sleeve rotatable in either direction away from a neutral position; motion transmitting means 40 responsive to a relatively slight turning motion of the sleeve away from neutral position for operating the reversing means; and motion transmitting means responsive to a relatively greater turning motion of the sleeve away from neutral position for closing the electric switch; whereby the operator may first select the direction of rotation and then start the motor by continued turning movement of the sleeve in the same direction.
